Patented Feb. 10, 1976

238,781

GUN SIGHT

Austin Behlert, 550 Boulevard,
Kenilworth, N.J. 07033

Filed Oct. 29, 1974, Ser. No. 518,597

Term of patent 14 years

Int. Cl. D16—06

U.S. Cl. D22—8

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of a gun sight embodying my new design;

FIG. 2 is a left side elevational view thereof;

FIG. 3 is a right side elevational view thereof;

FIG. 4 is a top plan view thereof;

FIG. 5 is a back plan view thereof;

FIG. 6 is a bottom plan view thereof;

FIG. 7 is a perspective view of the second embodiment of a gun sight embodying my new design;

FIG. 8 is a left side elevational view thereof;

FIG. 9 is a right side elevational view thereof;

FIG. 10 is a top plan view thereof;

FIG. 11 is a back elevational view thereof;

FIG. 12 is a bottom plan view thereof.

I claim:

The ornamental design for a gun sight, as shown and described.
